UNITED STATES PATENT OFFICE.

JOSEPH SCOTT ROGERS, OF GREENVILLE, ALABAMA, ASSIGNOR, BY MESNE ASSIGNMENTS, OF ONE-HALF TO FLORENCE D. METCALF, OF JOHNSON CITY, TENNESSEE.

DOUBLE PLOW.

Application filed April 2, 1921, Serial No. 458,057. Renewed March 12, 1923.

To all whom it may concern:

Be it known that I, JOSEPH S. ROGERS, a citizen of the United States, residing at Greenville, in the county of Butler and State 5 of Alabama, have invented certain new and useful Improvements in Double Plows, of which the following is a specification.

This invention relates to improvements in plows, and the primary object of the invention 10 is to furnish a duplex shovel which may be placed on a single stock plow to do the work ordinarily accomplished by a double stock plow.

A further object of the invention is to 15 provide the improved duplex shovel with means to permit a drag-board to be attached to the same.

Another object of the invention is to so 20 shape the duplex shovel that the shovel portions of the same will set accurately for proper working and facilitate its attachment to the ordinary heel bolt of the plow foot.

With the foregoing objects outlined and 25 with other objects in view which will appear as the description proceeds the invention consists in the novel features herein-after described in detail, illustrated in the accompanying drawing and more particularly pointed out in the appended claim.

Referring to the drawing:

Figure 1 is a perspective view of the improved duplex shovel showing the same attached to an ordinary single stock plow.

Fig. 2 is a top plan view of the same.

Fig. 3 is a side view.

Fig. 4 is a front view of the improved shovel.

In the drawings, 1 designates a plow beam provided at its rear end with two handles 2. 40 A foot member 3 is secured to the beam by means of U-bolts 4. The construction so far described is the same as that of an ordinary single stock plow and this forms no part of the present invention. To the foot member 3 is attached the improved duplex shovel 5, which is secured in place by means of the heel bolt 6 that passes through the heel portion of the foot member 3. The duplex shovel 45 is formed of a single piece of metal of U shape and the legs of the U-shaped member terminate in shovel portions 7. The legs incline outwardly and downwardly from their inner edges 10 to their outer edges 11 and thus the edges 10 function to cut the soil

and this soil is guided outwardly and rearwardly by the legs as the plow advances. 55

It will be noted that the cross-head portion 8 of the member 5 is curved upwardly in its longitudinal direction in order to accurately fit on the foot member 3 and to dispose the shovel portion 7 in correct position to work the soil. 60

The leg portions of the member 5 are provided with apertures 9 designed to receive chains used in attaching a drag-board to the plow. 65

It is to be understood that the stock illustrated in the present drawing forms no part of the present invention, the invention residing solely in the duplex shovel 5. 70

Every farmer has a plow stock that he uses on the farm for the purpose of plowing. The idea of the present invention is to furnish a duplex shovel which may be attached to any make of plow stock ordinarily employed by the farmer. 75

The duplex shovel eliminates the necessity of employing double plow stocks, and does the same work or better work than the double stock now in use. The improved duplex shovel may be practically employed for covering different varieties of seed in planting, such as cotton, corn, peanuts, rice, millet, potatoes, cane, etc., and may be used also in cultivating the above mentioned plants, just as they are coming up and begin to grow. 80

The plow may also be used in truck growing such as bedding up beds for planting small seeds such as truck growers use. Furthermore, the duplex shovel may be manufactured with less expense than the double plow stock and may be handled much easier than the double stock. The double stock now in use is a very difficult plow to keep in shape and is very unhandy to export. For instance, if a farmer has a portion of land that he desires to plant in peanuts and this land lies at a distance across his plantation, he has to hitch his team up to his wagon to take his single stock and double stock over 95 to do the work. With a single plow stock he prepares the land for planting, drops the seed, and then he has to unhitch from the single plow stock and hitch to the double plow stock to cover the peanuts. With the improved duplex shovel for the same work it would be unnecessary to transport the double stock at all, as the farmer could place 100 105

his single stock plow and a duplex shovel on the back of one horse and upon arriving at the place of planting he could first operate with the single plow and then substitute 5 the duplex shovel for the shovel of the single stock and complete the work. It will thus be seen that the improved duplex shovel may be advantageously employed with a single plow stock.

10 It is believed from the foregoing description taken in connection with the drawing that the construction and operation of the duplex shovel may be readily understood.

What is claimed and desired to be secured 15 by Letters-Patent is:

A duplex plowshare consisting of a U-

shaped metallic member formed of a single piece of metal and including a cross-head and leg members terminating in pointed shovel portions, the cross-head being concavo-convex in its longitudinal direction and being inclined transversely from its rear edge downwardly towards its front edge, the ends of the cross-head being lower than the central portion of the cross-head and merging into the leg members, and each of said shovel portions being concavo-convex in its longitudinal direction and inclined transversely from its inner edge downwardly towards its outer edge.

In testimony whereof I affix my signature.

JOSEPH SCOTT ROGERS.
